ADJUSTABLE ERASER

Frank C. Peterson, Randolph, Mass.

Application November 15, 1944, Serial No. 563,533

4 Claims. (Cl. 120—38)

1

This invention relates to an adjustable eraser, and the primary object of the invention is to provide a device of this kind which is comparatively simple in construction, durable, and efficient in operation.

More specifically, the present invention contemplates the provision of an adjustable eraser including a tube that may be secured on the upper end of a pencil, an eraser longitudinally slidable in the tube, a cap rotatable on the upper end of the tube and provided with gear teeth, said cap having a central opening through which the eraser projects, feed rollers journaled in and arranged transversely of the tube at the upper end of the latter and respectively engaging opposite sides of the eraser, and means operatively connecting said feed rollers with the gear teeth, whereby turning of the cap will effect longitudinal adjustment of the eraser.

The exact nature of the present invention will be readily understood from the following description when considered in connection with the accompanying drawings.

In the drawings, wherein like reference characters indicate corresponding parts throughout the several views:

Figure 1 is an elevational view of a pencil equipped with an adjustable eraser attachment constructed in accordance with the present invention.

Figure 2 is an enlarged central longitudinal sectional view of the attachment shown in Figure 1.

Figure 3 is an enlarged transverse section taken on line 3—3 of Figure 2.

Figure 4 is an enlarged end elevation looking to the left of Figure 2.

Figure 5 is a view similar to Figure 1 of a modified form of the invention.

Figure 6 is a view similar to Figure 2 of the attachment shown in Figure 5.

Figure 7 is a section of the plane of line 7—7 of Figure 6, with the cap and eraser omitted.

Figure 8 is a view similar to Figure 4 of the device shown in Figure 5.

Figure 9 is a view, similar to Figure 2, of a further modification.

Referring in detail to the drawings, the present attachment includes a tube 5 that may be adapted to be secured on the upper end of a pencil 6 and that is preferably divided into a lower pencil end-receiving chamber 7 and an upper eraser-receiving chamber 8 by means of a transverse partition 9. While any suitable means may be employed to secure the tube 5 on the

2

pencil 6, the lower end of said tube is preferably internally threaded, as at 10, so that the lower end of the tube may be screwed into the pencil. An eraser 11 is longitudinally slidable in the tube 5, and a cap 12 is rotatable on the upper end of the tube and is provided with tangential gear teeth 13 which, as shown in Figures 1 to 4 inclusive, are formed on the upper surface of an inwardly projecting flange 18 provided on the inner or lower end of cap 12. The cap 12 has a central opening 14 through which the eraser projects, and feed rollers 15 are journaled in the tube at the upper end of the latter. The rollers 15 respectively engage opposite sides of the eraser. In Figures 1 to 4, the rollers have shafts 16, respectively at opposite ends thereof, which project into the cap 12. Pinions 17 are secured on the shafts 16 and mesh with the gear teeth 13, whereby turning of the cap 12 will effect longitudinal adjustment of the eraser. Obviously, the eraser may be adjusted outwardly or inwardly, depending upon the direction of rotation of the cap 12, so that the eraser may be positioned to have the desired amount or portion thereof projecting outwardly beyond the cap. The teeth of the pinions 17 are formed to properly mesh with the tangential gear teeth 13. It will be seen that the cap 12 is retained in place upon the upper end of the tube 5 by engagement 20 of the flange 18, which carries the gear teeth 13, beneath the pinions 17. A very simple and durable attachment is thus provided which is efficient in operation, easy to use and economical to manufacture.

In the embodiment of Figures 5 to 8, inclusive, the rollers 15' are in the form of worm pinions disposed to project through slots provided in opposite sides of tube 5'. The rollers 15' are geared to the cap for rotation thereby in that 30 they directly mesh with internal worm gear threads 13' provided on cap 12'. In this form, the cap 12' is retained in place by spinning the flange 18', which is provided on the lower end of cap 12', inwardly into an annular external groove 19 provided in the tube 5'. Rotation of cap 12' in this form causes rotation of rollers 15' so that the latter adjust the eraser inwardly or outwardly, depending upon the direction in which cap 12' is rotated.

In the modification of Figure 9, the cap 12a is retained in place by spinning the flange 18a into groove 19a, but the pinions 17a are secured on shafts 16a within tube 5a and mesh with gear teeth 13a of a cylindrical flange rigid with the

top of cap 12a and projecting into tube 5a outwardly of rollers 15a.

The invention is simple, compact and efficient, and all forms operate in substantially the same manner.

What I claim as new is:

1. An adjustable eraser attachment for pencils, comprising a tube adapted to be secured on the upper end of a pencil, an eraser longitudinally slideable in the tube, a cap rotatable on the upper end of the tube and provided with gear teeth, said cap having a central opening through which the eraser projects, feed rollers journaled in and arranged transversely of the tube at the upper end of the latter and respectively engaging opposite sides of the eraser, said feed rollers having shafts respectively at opposite ends thereof projecting into the cap, and pinions secured on said shafts and meshing with the gear teeth, whereby turning of the cap will effect longitudinal adjustment of the eraser.

2. An adjustable eraser attachment for pencils, comprising a tube adapted to be secured on the upper end of a pencil, an eraser longitudinally slideable in the tube, a cap rotatable on the upper end of the tube and provided with gear teeth, said cap having a central opening through which the eraser projects, feed rollers journaled in and arranged transversely of the tube at the upper end of the latter and respectively engaging opposite sides of the eraser, said feed rollers having shafts respectively at opposite ends thereof projecting into the cap, and pinions secured on said shafts

and meshing with the gear teeth, whereby turning of the cap will effect longitudinal adjustment of the eraser, said cap having a flange disposed beneath the pinions to retain the cap on the tube.

5. An adjustable eraser attachment for pencils, comprising a tube adapted to be secured on the upper end of a pencil, an eraser longitudinally slideable in the tube, a cap rotatable on the upper end of the tube and provided with gear teeth, said cap having a central opening through which the eraser projects, feed rollers journaled in and arranged transversely of the tube at the upper end of the latter and respectively engaging opposite sides of the eraser, said feed rollers having shafts respectively at opposite ends thereof projecting into the cap, and pinions secured on said shafts and meshing with the gear teeth, whereby turning of the cap will effect longitudinal adjustment of the eraser, an inwardly projecting annular flange on the inner end of the cap, said flange having said gear teeth on the upper surface thereof.

20 25 30 4. An adjustable eraser, comprising a tube, an eraser longitudinally slideable in the tube, a cap rotatably secured on the upper end of the tube and having a central opening through which the eraser projects, rotatable feed rollers carried by the tube, and respectively engaging opposite sides of the eraser, and means gearing the feed rollers to the cap, whereby turning of the cap will cause rotation of the feed rollers for longitudinally adjusting the eraser.

FRANK C. PETERSON.
